UNITED STATES PATENT OFFICE.

WILLIAM S. RICHARDSON, OF BOSTON, MASSACHUSETTS.

DESIGN FOR A SOCKET MEMBER FOR SEPARABLE FASTENERS.

SPECIFICATION forming part of Design No. 27,536, dated August 17, 1897.

Application filed June 23, 1897. Serial No. 641,998. Term of patent 14 years.

To all whom it may concern:

Be it known that I, WILLIAM S. RICHARDSON, a citizen of the United States, residing at Boston, in the county of Suffolk and State of Massachusetts, have invented and produced a new and original Design for the Socket Member of a Separable Fastener, of which the following is a specification, reference being had to the accompanying drawings, forming a part thereof.

In the drawings, Figure 1 is a view in perspective of said design. Fig. 2 is a view of the same in perspective, inverted. Fig. 3 is a view of the same in cross-section.

The socket member has the flange a , which

may or may not be perforated and which is circular in shape, a cylindrical wall a' extending therefrom and at a right angle thereto, and a conical wall a^2 extending inward from the edge of the wall a' to the opening a^3 . 20

Having described my invention, what I claim as new, and desire to secure by Letters Patent of the United States, is—

The design for a socket member of a separable fastener herein shown and described. 25

WILLIAM S. RICHARDSON.
